**COMBINED BUMPER AND DUST COVER FOR
GASOLINE DISPENSING NOZZLE**

George H. Sinclair, Richmond Heights, and Wayne H.
Rush, St. Louis, Mo.

Application August 12, 1955, Serial No. 37,434

Term of patent 14 years

(Cl. D52—2)

FIG.1.

FIG.2.

FIG.3.

FIG.4.

FIG.5.

Fig. 1 is a side elevational view of a combined bumper and dust cover for gasoline dispensing nozzle, embodying our new design, with a dispensing nozzle shown in broken lines for purposes of illustration,

Fig. 2 is a front elevational view of the bumper and dust cover,

Fig. 3 is a top plan view of the bumper and dust cover,

Fig. 4 is an elevational view showing the back of our bumper and dust cover, and

Fig. 5 is a horizontal sectional view taken along line 5—5 of Fig. 1.

We claim:

The ornamental design for a combined bumper and dust cover for gasoline dispensing nozzle, substantially as shown and described.
